(57) **CLAIM**

The ornamental design for a bug teether, as shown and described.

DESCRIPTION

FIG. 1 is a top plan view of a bug teether, according to my design.

FIG. 2 is a front elevational view of a bug teether, according to my design; and,

FIG. 3 is a perspective view of a bug teether, according to my design.

The broken lines in the drawings represent unclaimed environmental subject matter and form no part of the claim.
